UNITED STATES PATENT OFFICE.

KEITH WILLIAMS, OF CHICAGO, ILLINOIS, ASSIGNOR TO WILLIAM H. MINER, OF CHAZY, NEW YORK.

GAUGE.

Application filed June 13, 1921. Serial No. 476,993.

To all whom it may concern:

Be it known that I, KEITH WILLIAMS, a citizen of the United States, residing at Chicago, in the county of Cook and State 5 of Illinois, have invented a certain new and useful Improvement in Gauges, of which the following is a full, clear, concise, and exact description, reference being had to the accompanying drawings, forming a part of 10 this specification.

This invention relates to improvements in gauges.

In the manufacture of what are known as Miner friction draft gears, one of the elements employed is a wedge of peculiar formation. Said wedge has three wedge faces, a cross-section through which produces an equilateral triangle. At the inner end of said wedge, that is, at the point of the wedge 20 of the least cross-section, outwardly-turned shoulders are formed which act as stops for certain anti-friction rollers. An illustration of such a Miner friction draft gear employing a wedge of the character described may 25 be found in O'Connor Patent No. 1,220,264, dated March 27, 1917. On account of the peculiar formation of the wedge, it has been found difficult to accurately gauge the wedge by any ordinary means.

30 The object of my invention is to provide a simple and efficient gauge for determining the accuracy of the angles between the wedge faces and the cross-sectional area of wedges of the character hereinbefore described.

35 Other objects of the invention will more clearly appear from the description and claims hereinafter following.

In the drawing forming a part of this specification, Figure 1 is a top plan view 40 of a gauge embodying my improvements. In this figure, the wedge to be measured is indicated in dotted lines. Figure 2 is a vertical sectional view corresponding substantially to the line 2—2 of Figure 1. Figure 45 3 is a detail sectional view corresponding substantially to the line 3—3 of Figure 1 and illustrating a portion of the wedge in section. Figure 4 is a broken view corresponding to Figure 1, illustrating the use 50 of a certain attachment for wedges of different size. And Figure 5 is an end view of the attachment shown in Figure 4 and illustrating by dotted lines the manner of applying it to the gauge proper.

Referring first to the construction illustrated in Figures 1, 2 and 3, the gauge is shown as embodying, broadly, a frame A; a fixed guide or tube B; a second pivotally mounted guide or tube C; a lever D; and a third guide or tube E.

The frame A, as shown, is of elongated loop formation having substantially semi-circular ends 10 and 10^a united by straight sections 11—11. The end 10^a is slightly offset from the remainder of the loop A for 55 the purpose hereinafter described. On the back or upper section, as it appears in Figure 1, there is applied rigidly the stationary guide or tube B, which is preferably in the form of a hollow tube of one-inch diameter 60 and corresponding to the anti-friction rollers employed in said Miner friction draft gears. Said tube or guide B may be secured to the frame by any suitable means—as, for instance, the spacers 12—12 and securing 65 rivets 13, as best shown in Figure 2.

The tube or guide C, which is preferably of hollow form and of one-inch diameter, similar to the tube or guide B, is pivotally mounted, as by means of the pivot pin 14, 70 on a radially inwardly-extended arm 15 rigid with the frame A. Said tube or guide 75 C has secured thereto an indicator arm 16 having a scale 17 at its outer end that cooperates with a zero mark 18 on the frame 80 A to indicate the angular position of the 85 guide C with respect to its pivot 14.

The lever D preferably consists of two plates 19 and 20, which straddle the section 10^a of the frame, and as the plate section 10^a, as shown in Figs. 1 and 2, is downwardly offset with reference to the end 10 and the sections 11, the upper plate 19 is brought substantially in line with the main portion of the frame A. Said two plates 90 19 and 20, constituting the lever, are pivotally attached to the main frame A, as indicated at 21, at a point substantially axially in line with the fixed guide or tube B. The lever 19—20 is of arcuate form adjacent its 95 pivotal end, as best shown in Figure 1 at 20^a and from the plate 20 is extended radially inward toward the center of the gauge an arm 22, to which is pivotally connected, as by means of the pin 23, the guide or tube E, 100 which is also similar to the stationary guide or tube B. Attached to the tube or guide E and extending radially outwardly there-

from is an indicator arm 24 having a scale 25 thereon adapted to co-operate with a radially-extending zero mark 26 similar to the indicator 17-18. In addition, the section 10^a of the main frame is provided with another indicator scale, as indicated by the series of lines 27-27 arranged at right angles to the zero line 26, and with which is adapted to co-operate the outer straight edge 28 of the indicator arm 24.

10 Rigidly secured to the stationary frame A is a suitable handle 29 and to the outer end of the lever D is secured another handle 30.

15 The location and arrangement of the guides or tubes B, C and E are such that when applied to a wedge of true equilateral triangular cross-section of the proper area, which wedge is indicated in dotted lines at 20 31 in Figure 1, the zero of the scale 17 will come opposite the zero line 18; the zero of the scale 25 will come opposite the zero line 26; and the edge 28 of the indicator arm 24 will come opposite the zero line of the scale 25 27-27. Furthermore, the pivotal points 14 and 23 will be equally spaced from the center 32 of the fixed guide or tube B.

25 The operation is as follows. The operator first swings the lever 30 in an opening 30 direction, as indicated by the arrow *b*. The wedge is then inserted with the proper portion thereof in engagement with the two guides or tubes B and C. The lever 30 is then swung back to its operative position 35 in the direction indicated by the arrow *a*. The lever D is then forced as far toward the stationary handle 29 as possible and the readings then taken. If the cross-section of the wedge is of true equilateral triangular 40 cross-section, and of the proper area, zero readings will obtain in each instance, as shown in Figure 1. If, however, the cross-sectional area (regardless of the true equilateral triangular cross-section) is greater 45 or less than the standard, the guide or tube E will obviously assume a position to either side of its proper position shown by the full lines in Figure 1, and the corresponding readings will be found on the scale 27-27. 50 Again, if the angle between the two faces in engagement with the guides B and E is correct—that is, 60°—but the angle between the face in engagement with the guide C and either of the other faces is greater or less 55 than 60°, the guide C will be correspondingly oscillated about the pivot 14, and the variation will be indicated by the scale 17. Similarly, if the face of the wedge in engagement with the guide E extends at an 60 angle greater or less than 60°, with the face of the wedge in engagement with the guide B, the variation will be indicated by the scale 25.

65 The arrangement shown may be used by unskilled labor; the readings are produced

substantially automatically; the device gauges for variations in both angle of the faces and area; and the gauging accurately determines the position which will be assumed by the anti-friction rollers to be used 70 with the wedge. By having the two-piece lever D straddle the section 10^a of the main frame, all possibility of the lever D being deflected upwardly or downwardly is positively prevented.

75 To adapt my improved gauge for similar wedges but of less cross-sectional area, I may employ an attachment indicated at F in Figures 4 and 5. This attachment consists merely of a semi-cylindrical tube 132 having 80 spaced pairs of spring arms 33-33 adapted to snap over the stationary guide B. A centering pin 34 is formed on the attachment F, said pin being adapted to enter a hole 35 in the stationary guide B. The ends of the semi-cylindrical tube 132 are tapered or beveled, as indicated at 36-36, so as to adapt the attachment to partially enter between the adjacent ends of the guides C and E. It will be noted that the attachment does not affect the question of angles 85 between the faces of the wedge, but does affect the area of the cross-section of the wedge at the point which is gauged.

90 I have herein shown and described what 95 I now consider the preferred manner of carrying out the invention, but the same is merely illustrative and I contemplate all changes and modifications that come within the scope of the claims appended hereto. 100

I claim:

1. In a gauge of the character described, the combination with a suitable frame; of a fixed guide thereon; a second guide pivotally mounted with respect to said frame; a lever 105 pivotally attached to said frame; and a third guide pivotally attached to said lever, said three guides, when all are in operative position, defining a triangular opening.

2. In a gauge of the character described, the combination with a suitable frame; of a fixed guide on said frame; and two additional guides pivotally adjustable with respect to said first-named guide, said three guides, when all are in operative position, 115 defining a triangular opening.

3. In a gauge of the character described, the combination with a rigid frame; of a fixed guide on said frame; a second guide pivotally attached to said frame; a member 120 movably mounted on said frame; and a third guide pivotally mounted on said member.

4. In a gauge of the character described, the combination with a suitable frame; of a 125 fixed guide on said frame; two additional guides pivotally adjustable with respect to said first-named guide, said three guides, when all are in operative position, defining a triangular opening; and co-operable means 130

on the frame and each of said pivoted guides arranged to indicate the angular position of each guide with respect to its pivot.

5. In a gauge of the character described, 5 the combination with a rigid frame; of a fixed guide on said frame; a second guide pivotally attached to said frame; a member movably mounted on said frame; a third guide pivotally mounted on said member; 10 and co-operative means carried by said third guide and the frame to indicate the relative proximity of the pivot of said third guide to the remaining guides.

6. In a gauge of the character described, 15 the combination with a rigid frame; of a fixed guide on said frame; a second guide pivotally attached to said frame; a member movably mounted on said frame; a third guide pivotally mounted on said member; 20 co-operative means carried by said third guide and the frame to indicate the relative proximity of the pivot of said third guide to the remaining guides; and co-operative means on the frame and each of said pivoted 25 guides arranged to indicate the angular position of each guide with respect to its pivot.

7. In a gauge of the character described, the combination with a frame; of a fixed guide thereon; a second guide pivotally 30 attached to said frame; a lever pivotally attached to said frame; a third guide pivotally attached to said lever; and indicator means carried by the frame and said third guide arranged to indicate the position of 35 the pivot of said third guide with respect to the other two guides.

8. In a gauge of the character described, the combination with a loop-shaped rigid frame having indicating means thereon; of 40 a fixed guide carried on said frame; a second guide pivotally attached to said frame; a radially-extending indicator arm carried by said guide and radially extending from said pivotal connection, and co-operative 45 with said indicating means; a lever pivot-

ally attached to said frame; a third guide pivotally mounted on said lever; an indicator arm rigid with said guide and extending radially from said pivotal connection; indicating means on said frame and last-named indicator arm adapted to indicate the angular position of said third guide with respect to its pivot; additional indicating means on said frame and indicator arm of the third mentioned guide arranged to indicate the relative position of the pivot of the third guide with respect to the remaining guides; a fixed handle carried by the frame; and a handle carried by said lever.

9. In a gauge of the character described, 60 the combination with a loop-shaped rigid frame; of a fixed guide carried on said frame; a second guide pivotally attached to said frame; a radially-extending indicator arm carried by said guide and radially extending from said pivotal connection and co-operative with indicating means on the frame; a lever pivotally attached to said frame; a third guide pivotally mounted on said lever; an indicator arm rigid with said 65 guide and extending radially from said pivotal connection; indicating means on said frame and last-named indicator arm adapted to indicate the angular position of said third guide with respect to its pivot; additional 70 indicating means on said frame and indicator arm of the third mentioned guide arranged to indicate the relative position of the pivot of the third guide with respect to the remaining guides; a fixed handle carried by the frame; and a handle carried by said 75 lever; each of said guides being of tubular formation.

In witness that I claim the foregoing I have hereunto subscribed my name this 9th 80 day of June, 1921.

KEITH WILLIAMS.
